UNITED STATES PATENT OFFICE.

HARRY FIRMAN, OF WOODHAVEN, NEW YORK.

LAMP SHADE.

Application filed April 25, 1923. Serial No. 634,564.

To all whom it may concern:

Be it known that I, HARRY FIRMAN, a citizen of the United States, residing at Woodhaven, L. I., in the county of Queens 5 and State of New York, have invented new and useful Improvements in Lamp Shades, of which the following is a specification.

This invention relates to lamp shades.

Some of the objects of the present invention are:—to produce a lamp shade which is especially adapted for use in connection with electric lamps for a full or effective distribution of the light emitted by the lamp or lamps with which it is associated; 10 to produce a lamp shade which is so constructed as to be attractive in appearance and one which not only reflects the light-rays but which also permits light to pass through portions thereof; to produce a 15 lamp shade which comprises a frame stamped, bent and formed from a single piece of material, and translucent panels arranged on the frame in inclined and circumferential relationship by virtue of the 20 construction of the panels and the frame, the latter having attaching means for attaching the lamp shade; to produce a lamp shade including a frame having means for attaching the lamp shade and means for 25 effecting the attachment of a lamp globe or the like; and with these and other objects in view the invention resides in the particular provision, relative disposition, and functions of the parts hereinafter fully 30 described and illustrated in the accompanying drawing, in which:

Figure 1 is a plan view of the lamp shade embodying the features of the present invention.

Figure 2 is a sectional view taken on the line 2—2 Figure 1.

Figure 3 is a perspective view of one of the translucent panels.

Figure 4 is an enlarged detail sectional view taken on the line 4—4 Figure 1.

Referring now more particularly to the several views of the drawing for the details it will be apparent that the lamp shade of the present invention is made up essentially 50 from a frame 10 and reflecting and light emitting panels 11 carried by said frame. The frame 10 is stamped, bent and formed from a single piece of material such as sheet-brass or the like to provide a rim 12 and

annular members 13 and 14 concentrically 55 arranged with respect to each other and to the rim 12. The rim 12 has an upturned annular portion 15. The rim 12 and the annular member 13 are joined by radially disposed members 16 which are spaced equidistantly and each of which is reinforced by a bead 17 to give strength thereto. The members 16 are disposed at an angle. The members 13 and 14 are separated by an intermediate top having holes 19 therein 60 for the circulation of air therethrough.

The panels 11 are made of glass and are translucent. Each of the panels is in the form of a trapezoid and curved. In the present instance five panels are employed 70 and are arranged on the members 15 and are held in place by clips 20 on the member 16 and clips 21 on the rim 12. Each of the clips 20 has bendable portions 22 which engage the edges of adjacent panels, whereas, 75 each clip 21 is bendable and engages one edge of its related panel. These clips 20 and 21 serve to hold the panel in place in circumferential relationship, and by virtue 80 of the inclination of the members 16 of the said panel 11 will also be inclined.

In order that the lamp shade may be attached to a lamp fixture the member 14 is provided with a ring 23 attached to the member 14 as at 24 and the free terminals 85 of the ring 23 which extend through an opening in the member 14 carry a binding screw 25 by virtue of which clamping action may be set up in the ring 23. In order 90 that an ornamental globe or the like may be held in place associated with said lamp shade and about the lamp there is provided set screws which are carried by the members 13.

From the foregoing it will be manifest 95 that there has been described a lamp shade whose features of construction are simple and which embodies means in the form of panels 11 for effectively distributing the light in the room by partly reflecting the light downwardly and at the same time admitting light through the panels to illuminate above the shade; and one which may be associated with one or more electric lamps or a single lamp fitted with an ornamental globe or the like to make an artistic and novel effect and at the same time having utility.

What is claimed is:

A lamp shade comprising a frame formed of an annular inclined rim, an annular rim of a larger diameter having an upturned flange disposed below said annular inclined rim, radial extending downwardly inclined members connecting said rims, translucent panels of curved trapezoidal pattern sup-

ported by said rims and having their meeting edges overlying said members, and bendable clips carried by said members for engagement with the meetings edges of said panels. 10

In testimony whereof I have affixed my signature.

HARRY FIRMAN.
